UNITED STATES PATENT OFFICE.

HOWARD W. RUSSELL, OF COLLINGSWOOD, NEW JERSEY.

BUCKLE.

Application filed February 5, 1926. Serial No. 86,113.

This invention relates to a buckle, clasp or hasp which is more particularly intended for connecting a strap to the front wall of a brief case or traveling bag although the same may also be used for a variety of other purposes in which similar conditions exist.

This invention has for its object the provision of such a buckle which has means whereby the strap is securely held in its locked or adjusted position and which permits of conveniently releasing the strap and shifting the same from one position to another relatively to the buckle and still preserve a compact and neat appearing construction and one which is not liable to get out of order.

In the accompanying drawings:

Figure 1 is a front elevation of a brief case provided with my improved buckle and showing the same utilized for connecting one of the straps with the front wall of the case.

Figure 2 is a vertical section taken on the correspondingly numbered line in Fig. 1.

Figures 3 and 4 are cross sections taken on the correspondingly numbered lines in Fig. 1.

Figure 5 is a fragmentary section similar to Fig. 2 but showing the strap lifted out of engagement from the adjusting pin on the base plate of the buckle.

Figure 6 is a perspective view of the buckle.

Similar characters of reference indicate corresponding parts in the several views of the drawings.

The numeral 10 represents the front wall of a brief case, 11 the upper flap thereof which closes against the front wall and 12 one of the fastening straps which is attached at its upper end to the flap 11 and adapted to be connected at its lower end with the front wall by means of the buckle 15 which is constructed in accordance with my improvements. This strap is provided with a longitudinal row of openings 13, the same being preferably arranged midway between opposite edges of this strap.

This buckle may be variously organized and associated with other parts but in the present case the same is so constructed that it is not only capable of adjustment lengthwise of the strap but also capable of vertical adjustment on the front wall of the

brief case. In the particular form of the buckle as here shown the same comprises a base plate 14 which is adapted to be engaged on its front side by the strap 12 and is provided on its central part with a forwardly projecting adjusting pin 15 adapted to engage with one or another of the longitudinal row of openings 13 in the strap for the purpose of adjusting the position of the buckle on the strap lengthwise of the latter and adapting the capacity of the brief case to the volume of material which is to be stowed therein.

On its rear side the base plate is provided with a button having an elongated head 16 and a reduced neck 17 forming a T-shaped structure which is adapted to engage with one or another of a longitudinal row of slots 18 formed in an adjusting plate 19 which is mounted on the front wall of the brief case and thereby permit of adjusting the buckle vertically on this wall in order to permit of a further adaption of the size of the case to the amount of material which is to be carried therein. This adjusting plate forms the web of a channel shaped member, the flanges or legs 20 at opposite longitudinal edges of which are secured to the front wall of the brief case by means of rivets 21, as shown in the drawings or by any other suitable means.

At its upper and lower ends the base plate 14 is provided with transverse loops 22, 23 which receive the adjacent parts of the strap 12 and in which this strap is capable of sliding lengthwise when it is detached from the adjusting pin 15. Detachment of the strap from this pin to permit of such sliding is effected by lifting that part of the strap or moving the same outwardly from the base plate into the form of an arch so that the respective adjusting openings 13 of the strap is wholly detached from the adjusting pin, as shown in Fig. 5. While the strap is in this position the same may be freely moved lengthwise of the buckle into the required position and thereafter the bowed part may be again released and assume a straightened position over the base plate with another one of its openings 13 in engagement with the adjusting pin 15, thereby retaining the buckle and strap against lengthwise displacement relatively to each other.

My invention relates more particularly to

- means whereby that portion of the strap between the loops 22 and 23 is reliably held in engagement with the base plate and interlocked with the adjusting pin while the buckle is in use and also permits of conveniently withdrawing that part of the strap between these loops so that the same is bowed forwardly and enables the strap to be readily adjusted lengthwise of the buckle.
- 10 In the preferred form of this improvement the same comprises a lifting arm 24 which is arranged in front of that part of the strap and the base plate between the loops 22 and 23 and is mounted at one end on one 15 of the loops while its opposite end is provided with a part which is adapted to engage with the under or rear side of the strap. In the preferred construction this lifting arm is constructed of a piece of thin, 20 springy, sheet metal which has sufficient resilience to constantly cause the free end of this arm to press rearwardly against the front side of the strap and hold the latter against the base plate 14 between its loops.
- 25 Although various means may be employed for mounting this lifting arm so as to form a unitary part of the buckle it is preferable to provide its upper or outer end with a rearwardly and reversely bent part or 30 tongue 25 which engages with a transverse groove 26 in the cross bar of the upper loop 22 and is preferably retained therein by spot-welding, although any other suitable means may be employed for this purpose.
- 35 The free inner end of this lifting arm is preferably provided with a notch 27 which straddles the adjusting pin in a normal position of the parts, whereby the free end of this adjusting arm is interlocked with this 40 pin and held against lateral displacement in case the same should brush against or come in collision with another object while the brief case or bag is being handled, thereby preventing the buckle from getting out of 45 order under such circumstances.
- The means whereby an outward or forward movement of the free end of the lifting arm is caused to engage with the rear or inner side of the strap preferably consists of two hooks 28 which are arranged 50 at opposite longitudinal edges of the lifting arm transversely in line with the adjusting pin 15 and projecting rearwardly along opposite longitudinal edges of the strap and into engagement with the rear side of the same, as shown in Fig. 3. To permit the hooks to thus engage with the rear side of the strap the central parts of the longitudinal edges of the base plate are cut away, as 55 shown at 29, thereby forming clearance spaces or notches on this base plate which uncover or expose the rear side of the strap at these points and enable not only the hooks 28 to engage with the rear side of the strap but also permit the fingers to freely grasp

the opposite sides of the free end of the lifting arm which carries these hooks and raise the adjacent part of the strap which is held thereby so as to disengage or move the same off from the adjusting pin 15. When the 70 strap is thus disengaged from the adjusting pin the same may be freely moved lengthwise of the buckle for bringing the latter and the strap into the desired relation lengthwise thereof, as previously explained, and upon releasing the lifting arm its resilience will again press the strap toward the base plate and hold the respective opening 13 thereof, reliably in engagement with the adjusting pin 15.

In the particular organization of this buckle shown in the drawings the quick connection and disconnection of the buckle with the front side or wall of the brief case or bag is effected by means of the coupling button on the base plate 14 which may be engaged with one or another of the slots 18 in the web 19, and the normal adjustment of the capacity of the brief case or bag is preferably obtained by adjusting the strap 90 12 on the buckle.

This means of lifting the strap from the adjusting pin on the base plate preparatory to adjusting the strap and buckle lengthwise one relatively to the other and then pressing the strap back again over the adjusting pin is very simple and inexpensive in construction. The same is very efficient and reliable in operation and the same is so organized that it is not liable to get out of 100 order.

I claim as my invention:

1. A buckle comprising a base adapted to be mounted on a member and which is adapted to engage with the rear side of a strap having a longitudinal row of openings, a pin arranged on the front side of said base and adapted to engage with one or another of said openings, and a flexible arm mounted on said base and extending over the front side of said strap and having a part adapted to engage with the underside of said strap.

2. A buckle comprising a base adapted to be mounted on a member and which is adapted to engage with the rear side of a strap having a longitudinal row of openings and which has a loop adapted to receive said strap, a pin arranged on the front side of said base and adapted to engage with one or another of the openings of said strap, and a spring arm mounted at one end on said base and projecting over the front side of said strap and provided adjacent to opposite sides of said pin with hooks adapted to engage with the underside of the opposite edge portions of said strap.

3. A buckle comprising a base adapted to be mounted on a member and which is adapted to engage with the rear side of a strap having a longitudinal row of openings and

- which has a loop adapted to receive said strap, a pin arranged on the front side of said base and adapted to engage with one or another of the openings of said strap, and
- 5 a spring arm mounted at one end on said loop and provided at its opposite end with a hook which is adapted to engage with the underside of said strap adjacent to said pin.
4. A buckle comprising a base adapted to be mounted on a member and which is adapted to engage with the rear side of a strap having a longitudinal row of openings, loops arranged at opposite ends of said base and adapted to receive said strap and one of said
- 10 loops being provided on its outer side with a groove, a pin arranged on the front side of said base and adapted to engage with one or another of said openings, and a spring arm provided at one end with a reversely curved part which is secured in said groove and at 20 its opposite end with rearwardly projecting hooks adapted to engage with the underside of said strap adjacent to opposite sides of said pin.
- In testimony whereof I hereby affix my 25 signature.

HOWARD W. RUSSELL.
